UNITED STATES PATENT OFFICE.

HARRISON B. WALTER, OF CHICAGO, ILLINOIS, ASSIGNOR, BY MESNE ASSIGNMENTS,
TO CONTAINER CORPORATION OF AMERICA, OF CHICAGO, ILLINOIS, A CORPORA-
TION OF DELAWARE.

BOX.

Application filed April 11, 1925. Serial No. 22,288.

This invention relates to improvements in boxes made of fibre or paper board and consists of the matters hereinafter described and more particularly pointed out in the 5 appended claim.

The invention relates more especially to improvements in what is known as the "recessed" end box such as shown in Letters-Patent No. 1,125,782, heretofore granted to me on January 19, 1915, and other related 10 patents. Said box comprises a tubular body and two ends or heads, which are secured in place, one at the beginning of the loading operation and the other after the loading operation is completed, and are known as "end-loaders," due to the fact that the contents 15 are introduced and packed in the body through one end after the other end has been attached. Such boxes are of great strength, particularly at the ends and are in wide use.

In many cases it is desirable to use what is known as the "top-loader"—that is to say, a box wherein the tubular body of the 20 box includes flaps or cover wings adapted to open one side of the box and to close on the ends of the box, which are both applied and secured to the body when the box is set up for loading. The object of the present invention is to provide a recessed end box, 25 with all the advantages due to the construction of the ends of such a box, and with the additional feature of being capable of being used as a top loader, with closure flaps adapted to be opened up for loading after 30 the box has been set up and the ends secured in place and to be closed and sealed after the box is loaded.

Another object of the invention is to produce a top loading box, in which the closure flaps at the top side of the box may be sealed by means of a single sealing strip, without leaving any gaps or openings at the ends of the box.

These and other objects and advantages 45 of the invention will appear more fully as I proceed with my specification.

In the drawings:

Figure 1 is a perspective view showing the improved box as it appears when sealed and ready for shipping.

Figure 2 is a view in perspective showing the box partially opened up ready for packing.

In Figure 3 are shown plan views of the 55 several blanks which go to make up the box.

Figure 4 is a view representing in part a transverse section through the box, and in part an end elevation.

Figure 5 is a view showing a longitudinal section through the top part of the box. 60

Figure 6 is a perspective view of a somewhat different form of box provided with the invention.

Figure 7 is a perspective view of the box of Figure 6 opened up ready for packing. 65

Figure 8 is a view in which are shown the three blanks which go to make up the box.

Figure 9 is a view showing a partial, transverse section through the box.

Figure 10 is a view of a partial, longitudinal section through the box. 70

Referring now to that embodiment of the invention illustrated in the drawings and more particularly in Figures 1 to 5;—the box is made up of a body blank 10 and of two like end blanks 11, 11. The body blank is provided with parallel, longitudinally extending crease lines 12, which divide said blank into a bottom part 13, two side parts 14, 14 and narrow cover flaps or wings 15, 15. The end blanks 11 are each cut and creased to provide an end wall 16, two narrow side flaps 17, 17, a narrow bottom flap 18, and a narrow flap 19 at the top to which is connected a cover flap extension 20, which is adapted to fold along a crease line 21 back on the narrow flap 19. 80

The box is set up and the blanks are attached together in the well-known manner in which recessed end boxes are made, with the narrow side flaps 17, 17 secured to the marginal end parts of the side walls 14, 14 of the body blank and with the narrow bottom flap 18 secured to the marginal end part of the bottom wall 13 of said blank. The cover flap extensions 20, 20 are made of such length that when the two of them are folded over to close the body of the box, they will meet or butt at their ends, as shown in Figure 1, or will overlap, as shown in Figure 5. 90

The narrow flaps 17 and 18 of the end blanks are attached to the body blank by any familiar means, as by staples, stitching or other efficient attaching means. After the box is packed and ready for sealing the narrow cover wings 15, 15 connected to the sides 14, 14 of the body blank are turned down on the contents of the box and the end cover flap extensions 20 connected to the end blanks are then folded down upon 100 105 110

top of the side wings 15, 15, whereupon the box is sealed by the application of a transversely extending sealing strip 22, as shown in Figures 1 and 5.

- 5 It will be noted from an examination of Figure 5 that when the end flap extensions 20, 20 are folded down upon top of the side wings 15, 15, as above described, the marginal parts of the wings 15, 15 near the 10 ends of the box are embraced between the narrow flap 19 at the top of the end wall 16 and the end cover flap extension 20. Thus not only is a closure made, without 15 gaps, adjacent the end wall of the box, but in addition, a very strong construction is produced.

The one sealing strip 22 efficiently closes and seals the box. But, if desired and for purposes of additional strength, staples may 20 be applied to rigidly connect the cover flap extensions 20, the flaps 19 and the marginal parts of the side wings 15 embraced between them, rigidly together, as indicated by the staples shown at 25 in dotted lines in Figure 1.

The construction described presents a recessed end box in the form of a "top loader" and has all the advantages of strength at the ends of such a box, combined 30 with the convenience of packing of a "top loader." In addition, it has the advantage that the box may be absolutely sealed with the use of the one sealing strip, where, heretofore, it has been necessary to use three 35 sealing strips.

Instead of the sealing strip, the cover flap extensions 20, 20 may be sealed and attached to the cover wings 15, 15 (and to each other at their ends, when they overlap) by cement, 40 silica or other suitable material generally used in the art for attaching a board in flat engagement with another paper board. In such case the bottom surfaces of the cover flap extensions 20, 20 may be coated with the cementitious material before they are 45 folded down upon the narrow cover wings 15, 15, the top surfaces of which may also be coated with the cementitious material. A strong, efficient seal is thus provided.

50 In Figures 6 to 10, some features of the invention are shown in connection with a

flush-end box. Here like parts are indicated by the same numerals with the superfix "x." The end blanks in this case are reversed as compared to the construction 55 shown in Figures 1 to 5, so that the end walls 11x of the box are flush with the ends of the tubular body of the box. As the ends are not recessed in this case, the necessity for the narrow flap 19 at the top of the 60 blank is dispensed with, there being but the single cover flap extension 20x at the top of said blank. Here, again, the end cover flap extensions are made of such length as to butt together, as shown in Figure 6, or 65 to overlap, as shown in Figure 10. But, they are folded down upon the narrow side cover wings 15x of the body and are attached together by a single sealing strip 22x as before. 70

Both types of box illustrated represent manifestly a considerable saving in material when compared to the usual "top loader," since the necessity for extending the cover wings 15, 15 to cover the entire 75 top of the box is eliminated.

I claim as my invention:—

A top loading recessed end box comprising a body blank and two end blanks, the body blank being creased to provide the 80 bottom and two sides of the box and two side cover wings, each end blank being cut and creased to provide an end of the box, with narrow strips at the sides, bottom and top thereof, the side and bottom strips being attached within the marginal end of the body blank so that the end of the box is recessed within said body, and the top strip having a cover extension which folds back on said top strip, the two side cover wings 90 resting on the end top strips, and the two top cover extensions folding down upon the side cover wings and being sealed thereon, the side, bottom and top strips of each end blank cooperating with the body of the box 95 and the top cover extensions to form an outwardly extending reinforcing rib at each end of the box.

In testimony that I claim the foregoing as my invention, I affix my signature this 100 8th day of April, A. D. 1925.

HARRISON B. WALTER.
